UNITED STATES PATENT OFFICE

142,204

DESIGN FOR A FORK OR OTHER ARTICLE OF FLATWARE

James Russell Price, Cranston, R. I., assignor to
Gorham Manufacturing Company, Providence,
R. I., a corporation of Rhode Island

Application June 7, 1944, Serial No. 113,899

Term of patent 14 years

(Cl. D54—12)

To all whom it may concern:

Be it known that I, James Russell Price, a citizen of the United States of America, of No. 2335 Cranston Street, Cranston, Rhode Island, United States of America, have invented a new, original, and ornamental Design for a Fork or other Article of Flatware, of which the following is a specification, reference being had to the accompanying drawing, forming part thereof.

Fig. 1 is a front view of a fork, showing my new design; and

Fig. 2 is a side view of the same.

The essential features of the design reside in the handle shown in full lines.

I claim:

The ornamental design for a fork or other article of flatware, substantially as shown and described.

JAMES RUSSELL PRICE.
